UNITED STATES PATENT OFFICE.

JENNY A. VAN NEST, OF KANSAS CITY, MISSOURI.

APRON

Application filed March 25, 1926. Serial No. 97,236.

My invention relates to improvements in 55
aprons.

One of the objects of my invention is to 5
provide a novel apron, which has novel
means for being attached to a dress, so as
to present the appearance of being a part
thereof, and which eliminates the usual
apron strings.

A further object of my invention is to 10
provide a novel apron, which is simple,
cheap to make, easily donned, and which is
attractive in appearance.

The novel features of my invention 15
include further a dress having novel apron
attaching means adapted to co-operate with
my improved apron.

Hereinafter are described and claimed the
novel features of my invention.

In the accompanying drawing, which 20
illustrates the preferred embodiment of my
invention,

Fig. 1 is a front elevation of a dress pro-
vided with my improvement and having my
improved apron attached thereto.

Fig. 2 is a rear elevation of the same.

Fig. 3 is a plan view of my improved
apron.

Fig. 4 is a front elevation of my improved
dress, a portion of the button concealing tab
being broken away.

Similar reference characters designate
similar parts in the different views.

1 designates the body of a dress of the
general type of an ordinary house dress, and
which is provided at opposite sides thereof
with the usual two sashes 2, which are adapt-
ed for being fastened together in the back, as
by tying together, as shown in Fig. 2.

3 designates my improved apron, which
40 adjacent to opposite side edges is provided
with two slits or openings 4 adapted to have
the sashes 2 inserted therethrough respec-
tively, Fig. 1.

As shown, the distance between the open-
45 ings 4 is substantially the same as the dis-
tance between the juncture points of the
sashes 2 with the body 1 of the dress, meas-
ured across the front of the body.

The central upper portion of the apron
50 3 is provided at a point higher than the
openings 4 with a buttonhole 5 adapted to
receive therethrough a button or other suit-
able securing device 6, which is fastened to
the central front part of the dress body 1

at a point suitable for the attachment there-
to of the apron 3.

In order to cover and conceal the button
6 from view, a depending tab 7 is fastened
at its upper end to the dress body 1 adja-
cent to the neck opening 8. Normally the
tab 7 hangs over and covers the button 6.

In applying the apron to the dress, the
sashes 2 are inserted through the openings 4
and then tied together at the back, as shown
in Fig. 2. The sashes keep the apron from
slipping forwardly, as well as serving to
support the apron.

The button 6 is inserted through the but-
tonhole 5, after which the tab will hang in
front of and hide the button from view.

Preferably the apron 3 is made of ma-
terial similar to that of which the dress is
made, so as to present the appearance of
being a part thereof. A woman attired with
my improved dress and apron need not, in
order to present a good appearance, detach
the apron, when answering the door bell, or
when making short excursions from the
house, as the make up of the dress and apron
from the same kind of material, imparts the
impression to the observer that the apron
is a part of the dress. This impression is
further enhanced by the absence of the usual
apron strings.

I do not limit my invention to the struc-
ture shown and described, as modifications,
within the scope of the appended claims,
may be made without departing from the
spirit of my invention.

What I claim is:—

1. The combination with the body of a
dress and two sashes respectively attached
to opposite sides thereof and adapted to be
fastened together at the back, of an apron
adapted to be worn over the front of the
body of the dress and having two openings,
said two openings being spaced apart a dis-
tance substantially the same as the distance
between the juncture points of said sashes
with said body, measured across the front
of said body adapted to respectively receive
therethrough said sashes.

2. The combination with a dress body,
two sashes respectively attached to opposite
sides of the body and adapted to be fastened
together at the back, a securing device
fastened to said body higher than and in-
termediate of said sashes, and a tab fastened

to the front of the body and adapted to hang in front of said securing device, of an apron adapted to be worn over the front of said body and having three openings adapted to

5 respectively receive therethrough said sashes and said securing device, the two openings which receive said sashes being spaced apart

a distance substantially the same as the distance between the juncture points of said sashes with said body, measured across the 10 front of said body.

In testimony whereof I have signed my name to this specification.

JENNY A. VAN NEST.
